CLAIM

The ornamental design for a “bareback riding pad”, as shown and described.

DESCRIPTION

FIG. 1 is a perspective view of the bareback riding pad showing my new design in use;

FIG. 2 is a perspective view of the bareback riding pad of FIG. 1;

FIG. 3 is a right side elevation view thereof, (the opposite side being a mirror image);

FIG. 4 is a front elevation view thereof;

FIG. 5 is a top plan view thereof;

FIG. 6 is a rear elevation view thereof; and,

FIG. 7 is a bottom plan view thereof.

The broken line showing of a horse in FIG. 1 is for illustrative purposes only and forms no part of the claimed design.
